UNITED STATES PATENT OFFICE.

A C KNAPP, OF VICTORIA, ILLINOIS.

TORPEDO-GUARD FOR SHIPS.

1,324,904.

Specification of Letters Patent. Patented Dec. 16, 1919.

Application filed February 13, 1919. Serial No. 276,816.

To all whom it may concern:

Be it known that I, A C KNAPP, a citizen of the United States, residing at Victoria, in the county of Knox and State of Illinois, have invented certain new and useful Improvements in Torpedo-Guards for Ships; and I do hereby declare the following to be a full, clear, and exact description of the invention, such as will enable others skilled in the art to which it appertains to make and use the same.

This invention relates to torpedo guards, and more particularly to a guard specially adapted to be applied to ships for guarding or protecting the same from attacks by submarine boats.

One of the main objects of the invention is to provide a torpedo guard which will extend completely about the ship so as to protect the same from attacks by torpedoes from any quarter.

A further object is to provide a supporting structure adapted to fit about the ship so as to travel therewith, this structure being provided with a plurality of outwardly projecting arms which support protecting plates, these plates serving to effectually prevent a torpedo from contacting with the hull of the ship.

Another object is to provide means whereby, when one of the protecting plates is struck by a torpedo, a depth bomb will be automatically projected in the direction from which the torpedo is shot so as to injure or destroy the submarine boat which fired the torpedo.

Further objects will appear from the detailed description.

In the drawings:

Figure 1 is a top plan view of a guard constructed in accordance with my invention.

Fig. 2 is a side view of the same, as applied.

Fig. 3 is a transverse section.

Fig. 4 is a section taken on line 4—4 of Fig. 3.

Fig. 5 is a fragmental detail of the means for controlling the circuit of one of the guns.

Fig. 6 is a fragmental detail section through one of the guns, and parts associated therewith.

In carrying my invention into effect, I

provide a supporting structure which is adapted to fit about the hull of a ship, this structure comprising an upper frame 1 and a lower float frame 2, which is somewhat smaller than the upper frame, these two frames being rigidly secured together by brace beams 3 thus forming a framework or cradle which is adapted to fit about the hull of a ship so as to be propelled through the water therewith. This cradle is provided with horizontally projecting arms 4 rigidly secured thereto at their inner ends, the outer ends of these arms being secured to an outer float frame 5 which is normally positioned beneath the water surface. This float frame is of substantially rectangular cross section and conforms in outline to the crib structure. The outer float frame 5 is disposed in uniform spaced relation to frame 2 and disposed in the plane of the inner frame, these two float frames being rigidly connected by bracing and connecting members 7. Each of the arms 4 is provided in its outer end with a vertical slot or recess which snugly receives the inner end portion of a supporting arm 8 hingedly secured therein by a pivot bolt 9. As will be noted, this arm projects a short distance across the upper face of the outer float frame and is so connected to arm 4 as to have free upward movement about its axis, while having its downward movement positively limited by the float so as to normally project substantially horizontally therefrom. At its outer end, arm 8 is rigidly secured to a cross bar 10. This cross bar receives inwardly directed horizontal pins 11 which are slidable through openings provided through the cross bar for this purpose, these pins being secured at their outer ends to a substantially rectangular guard plate 12 which projects above and below bar 10. In practice, there are a relatively great number of these bars and plates provided, each supported by a pair of arms 8, and these plates are disposed with their ends closely adjacent, as shown in Fig. 1 of the drawings, so as to form a completely closed protecting wall about the hull of the ship.

An operating rod 13 is slidable through the bar 10 at the center thereof, the outer end of this rod being inserted through plate 12 and secured against movement therethrough in either direction by jam nuts 14.

At its inner end, rod 13 is pivotally secured in the bifurcated outer end of a rod 15 hinged at its inner end, as at 15°, to a rod 15^b slidable through a U-guide 16 secured on 5 the upper face of float frame 5.

Rod 15^b is normally held in outward position by an expansion coil spring 17 mounted about the rod and confined between an annular shoulder 18 formed on the rod and 10 a guide bracket 19 secured on the upper face of the inner float frame 2 and slidably receiving the inner end portion of the rod. At its inner end, this rod is pivotally connected to the lower arm of a bell crank lever 15 20 the upper arm of which is secured to a flexible member 21 for releasing a contact member 22 for movement into contact with two spaced contacts 23 connected to the opposite sides of an electric battery B. A gun 20 24 of suitable type is mounted upon the top frame 1 in a substantially horizontal position, this gun being provided with a suitable breech block 25 which carries an electrically controlled firing mechanism including members 22 and 23, and terminal members 25 associated therewith for igniting an explosive charge, contact 22 being carried by a plunger 22^a forced inwardly by an expansion spring 22^b, and normally held out 30 by a releasing rod 21^a to which member 21 is secured, this rod being normally held raised by an expansion spring 21^b. The gun is adapted to receive an explosive charge 26 for propelling a projectile 27 therefrom. 35 This projectile is in the form of a depth bomb, containing an explosive charge and being provided with a time fuse 28 which is adapted to be ignited simultaneously with firing of the cartridge. In practice, at least 40 one of these guns is positioned upon the top frame 1 in alignment with each guard plate. When any one of the plates is struck either by a torpedo, or by a submarine boat itself, the plate will be forced inwardly so as to 45 cause the gun to be fired thus discharging the projectile into the water over the guard plate, this projectile being exploded through the medium of the time fuse so as to injure or wreck the submarine. In the case of a 50 torpedo which is fired from a submarine boat, the projectile will be discharged in a straight line in the direction from which the torpedo was fired, so as to be positioned comparatively close to the submarine at the 55 time of its explosion. In the case of a submarine boat being struck by one of the guard plates, the gun will be fired thus giving a signal which will indicate accurately just where the submarine boat is positioned 60 and permit the same to be attacked with depth bombs of usual type. In either case the gun will act as a signal and, in the former case, will also act to propel the projectile in the direction from which the torpedo 65 is shot and to thus possibly seriously injure

or sink the submarine boat. In the event of a plate being struck by a torpedo which explodes, this plate and the associated parts can swing upwardly thus minimizing the effect of the force of the explosion and preventing serious injury to the ship or to the guard therefor. 70

It will be evident that there may be slight changes made in the construction and arrangement of the details of my invention 75 without departing from the field and scope of the same, and I intend to include all such variations, as fall within the scope of the appended claims, in this application in which a preferred form only of my invention 80 is disclosed.

What I claim is:

1. In a torpedo guard for ships, the combination of a supporting structure adapted to fit about the hull of a ship so as to be propelled therewith, float frames mounted in spaced relation with said supporting structure and rigidly secured thereto, supporting arms hingedly secured at their inner ends to the outer one of said float frames 85 for movement about horizontal axes, said arms having their downward movement positively limited so as to be normally disposed in a horizontal plane, guard plates supported by said arms at the outer ends 90 thereof in vertical position, said plates being mounted for movement toward and away from the ship hull, guns carried by said supporting structure and provided with electrically controlled firing mechanisms, one 95 gun being positioned in alignment with each of said guard plates, and means for closing the electric circuit for operating the firing mechanism of each of said guns when the corresponding guard plate is forced inwardly. 100

2. In a torpedo guard for ships, a supporting structure adapted to fit about the hull of a ship so as to be propelled therewith through the water, a float frame 110 mounted in substantially spaced uniform relation to the supporting structure, arms rigidly secured to said supporting structure and to the supporting frame for maintaining the same in proper spaced relation, supporting arms hingedly secured to the outer ends of the first mentioned arms for movement about horizontal axes, said supporting arms having their downward movement positively limited by the float frame so as 115 to be normally maintained in substantial horizontal position, a cross bar rigidly secured to the outer ends of said supporting arms, a guard plate supported by said cross bar for movement toward and away from 120 the same, an operating rod slidable through the cross bar and secured at its outer end to the guard plate, a rod hingedly secured at its outer end to the inner end of said operating rod, means for normally forcing said 125 130

rod outwardly so as to hold the guard plate spaced away from the cross bar through the medium of the operating rod, a gun carried by said supporting structure and provided 5 with an electrically controlled firing mechanism, and means connected to said operating rod so as to be operated thereby for closing the circuit of the firing mechanism of the

gun when said guard plate is forced inwardly.

In testimony whereof I affix my signature in presence of two witnesses.

A C KNAPP.
